UNITED STATES PATENT OFFICE.

JOHN M. CALLOW, OF SALT LAKE CITY, UTAH, ASSIGNOR TO GENERAL ENGINEERING COMPANY, OF SALT LAKE CITY, UTAH, A CORPORATION OF UTAH.

PUMP.

Application filed April 4, 1924. Serial No. 704,095.

To all whom it may concern:

Be it known that I, JOHN M. CALLOW, a subject of the King of Great Britain, residing at Salt Lake City, in the county 55
5 of Salt Lake, State of Utah, have invented certain new and useful Improvements in Pumps; and I do hereby declare the following to be a full, clear, and exact description of the invention, such as will enable others 60
10 skilled in the art to which it appertains to make and use the same.

The present invention relates to pumps, and particularly to diaphragm pumps capable of withstanding and working against 65
15 relatively high pressures. The object of the invention is to provide an improved pump of this type.

In carrying out many industrial processes, it is convenient to handle the various 70
20 liquors, pulps, and sludges encountered, by means of pumps. In many instances the pulps and sludges resulting from various processes of treatment are difficult to pump for the reason that they may contain relatively 75
25 large amounts of solid matter, and at other times gritty or abrasive material, which causes extremely rapid wear of the various parts of the pumps as they are usually constructed.

30 The present invention is therefore directed to the provision of a pump which is particularly well adapted to handle, not only all kinds of fluids, but also thick, gritty pulps and sludges, acids, and other corrosive liquids, and which is capable of operating 80
35 either as a suction pump or as both a suction and pressure pump so that it is readily adapted to raise such liquids and pulps to a relatively great height. At the same time 85
40 the pump is of extremely simple construction, easy to assemble, possesses inherent strength because of the characteristic shape of its various parts, and can be manufactured at a relatively low cost, and thereby 90
45 has a large and varied range of usefulness.

The pump constructed in accordance with the present invention comprises two relatively reciprocable members, such, for example, as two circular and substantially 100
50 parallel discs or plates which are connected together, at or near their peripheries, by a separately formed and self-sustaining annular diaphragm. The marginal edges of

the diaphragm are of substantially the same diameter and are each provided with a bead 55 or other means by which they may be easily clamped to the plates. The diaphragm is outwardly convex between these marginal edges throughout its entire periphery and is constructed of heavily reinforced material, such as heavily reinforced rubber, which is non-distensible and not particularly flexible, but which, at the same time, is capable of relatively slight transverse flexure at all 60 points from one margin thereof to the other 65 so that the margins may be moved with comparative ease with respect to one another through a relatively small distance as compared with the diameter of the annular diaphragm. 70

By the term "separately formed self-sustaining annular diaphragm" is meant a diaphragm which itself retains a definite configuration previously given to it by a separate manufacturing operation, as distinguished from a diaphragm that is cut from a piece of sheet material. A diaphragm of the latter type is difficult to secure to the pump plates, is inherently weak, and is necessarily given internal stresses in 80 forcing it into place upon the peripheries of the plates. By making the diaphragm outwardly convex throughout its peripheral surface, all irregularities or wrinkles or bellows-like surfaces are avoided, all of 85 which tend to localize the wear in certain portions of the diaphragm and, hence, at the time the diaphragm is installed, delineate the lines along which the diaphragm 90 will eventually crack. Moreover, the separately formed self-sustaining outwardly convex structure possesses extremely high inherent strength which enables it to withstand correspondingly high internal pressures. Such a structure also may easily be 95 heavily reinforced. The diaphragm of the present invention, however, is stressed, and therefore flexes, substantially uniformly from one margin to the other.

I have found that a pneumatic automobile 100 tire casing is particularly well adapted for use as such a diaphragm and prefer to employ such a tire casing, although, if desired, a specially constructed substantially tire-shaped diaphragm may be used. 105

In order that the invention may be more

fully understood, reference is made to the accompanying drawings illustrating, by way of example, a mechanical embodiment of the inventive idea. In these drawings:

5 Fig. 1 is a view in front elevation of a pump constructed in accordance with the invention;

Fig. 2 is a view in section taken on the line 2—2 of Fig. 1;

10 Fig. 3 is a central sectional view on an enlarged scale showing the relation of the parts of the pump and the means for securing the annular diaphragm in place; and

15 Fig. 4 is a diagrammatic view showing a modification of the pump in which the liquid being pumped is excluded from the pump chamber.

Referring first to Fig. 3 of the accompanying drawings, there are here shown a pair of 20 circular plates 10 and 11 which are disposed in substantially parallel relation and form the lower and upper walls of the pump respectively. These plates may be dished, as shown, or otherwise formed in order to secure the strength required. The lower plate 25 10 is provided with a central aperture 12 and is bolted to the stationary support 13 with the aperture 12 in alignment with a passageway therein which communicates with suitable inlet and outlet valves, the construction 30 and operation of which is well understood.

The upper plate 11 is reciprocable with respect to the lower stationary plate 10, and for this purpose is provided with a boss 14 35 for connection with a suitable driving mechanism. A separately formed self-sustaining outwardly convex diaphragm 15, such, for example, as an automobile tire, is secured at its marginal edges respectively to the periphery of the lower circular plate 10 and the upper or movable circular plate 11. The plates 11 and 10, therefore, form the upper and lower walls respectively of the pumping chamber and the annular diaphragm forms 40 the side wall thereof. One method of securing each of these marginal edges in place is as follows. An annular ring 16 having sloping surfaces adapted to engage the inner sloping surface of the annular diaphragm 45 is provided at the periphery of the circular plate. A second annular ring 17, so constructed as to conform to the shape of the bead 18, is placed upon the bead, and a third annular ring 19 is laid outside of the ring 50 17 and, by means of a plurality of bolts 20 which are threaded into the pump plates, serves to clamp the parts together. By this means pressure is exerted upon the ring 17 and bead 18 which wedges the margin of the 55 diaphragm between the sloping surface of ring 16 and the inner surface 21 of ring 17.

In Fig. 3, the movable plate 11 is shown at the inner end of its stroke with the diaphragm 15 in the normal configuration in 60 which it is made. The pump is operated by

moving the plate outwardly a relatively short distance as compared with the diameter of the plates 10 and 11, as is shown in dotted lines in Fig. 3, and as this movement takes place the marginal edges of the annular diaphragm 15 are separated from one another and cause the flexing of the material of the diaphragm substantially uniformly at all points between these edges.

70 While this upward motion or stroke of the plate 11 is taking place, the volume of the pumping chamber 22 formed between the plates and within the diaphragm is increased, and if the pump is connected to a source of liquid supply, liquid will be drawn 75 into this space; upon the downward movement or stroke of the plate 11, the liquid will be forced out of the chamber, all in a well understood manner. In order to assist in removing the air from the pumping chamber 80 22 when the pump is first placed in operation, or in removing any air which might accumulate therein in course of time, a valve 23, shown in Fig. 3 as a hand-operated 85 valve, is provided.

90 Referring now to Figs. 1 and 2, the hollow support 13 for the parts constituting the pumping chamber just described is mounted upon a base which is the metal plate 24. The support 13 is provided with inlet and outlet valves 25 and 26, respectively, through which the liquid to be pumped is admitted to and discharged from the interior of the support 13 and the pumping chamber 22 which is in direct communication therewith.

95 The base plate 24 is attached by means of the strengthening steel angle bars 27 to the lower portion of a suitable steel framework 28 which supports the various parts of the pump in proper relation with one another. Secured to this framework somewhat above the top of the diaphragm 15 there is a bearing 29 for an oscillating lever arm 30. The short end of this arm extends toward the front of the pump and immediately over the boss 14 bolted to the movable plate 11 of the pump and to which this end of the lever is connected through a forked link 31. The other end of the lever 30 extends rearwardly into substantially vertical alignment with a 100 rotatable driving shaft 32 which is mounted in suitable bearings 33 located at the upper part of the framework 28. An adjustable eccentric 34 is rigidly secured to shaft 32 and the strap 35 of this eccentric is connected 105 through the adjustable link 36 with the rear end of lever 30.

110 A pulley 37 mounted on one end of shaft 32 serves to rotate the shaft and cause the reciprocation of the upper pump plate 11 115 through the instrumentalities just described. The motion of the upper plate 11, that is, its length of stroke, can be varied by changing the stroke of the adjustable eccentric 34, and the output of the pump thus controlled 120 125 130

without changing the speed of rotation of the shaft 32.

When this pump is operated in connection with a supply of liquid or pulp, for example, 5 the pulp is drawn in through the inlet valve 25 on the upward stroke of the pump and fills the interior space of the hollow support 13, its connecting passages, and the interior of the pump chamber 22. Upon the down- 10 ward stroke of the pump, however, the inlet valve 25 closes and the outlet valve 26 opens, confining the pulp within the pump chambers and forcing it outwardly through the outlet valve.

15 By separately forming the diaphragm into an outwardly convex self-sustaining structure, all wrinkles or creases in either the interior or exterior surfaces of the dia- phragm are eliminated so that the wear of 20 the diaphragm caused by flexing is not local- ized in any particular regions but is evenly distributed throughout the entire structure 25 of the diaphragm. Moreover, a diaphragm of this character can be easily and advan- tageously reinforced to a high degree so as to provide exceptionally great strength.

A further consideration is the simplicity 30 of the entire pump structure, and in this connection may be mentioned particularly 35 the advantage arising from the use of a sep- arately formed and self-sustaining dia- phragm. Such a diaphragm can be mounted upon the peripheries of the pump plates 10 and 11 with great facility and by an ordi- 40 nary workman. The operation of securing 45 the diaphragm in place is also rendered easy by the use of a diaphragm the marginal edges of which are provided with a bead which may be readily clamped in place.

40 In Fig. 4 of the accompanying drawings, the pump is modified so as to exclude the possibility of the liquid being pumped enter- 45 ing the pumping chamber. In this modifi- cation the pulp or other liquid to be raised is drawn from a vessel 38 through an inlet 50 valve 39 and is discharged through an out- 55 let valve 40 and the pipe 41 into a vessel 42 at any desired elevation above that of the pump. The pump diaphragm 15 is oper- ated by mechanism similar to that above de- 60 scribed. The support for the lower or sta- tionary plate 10 of the pump, however, is enlarged and comprises a vertical cylindri- 65 cal casing 43 extending through the floor 44 upon which the pump rests.

Attached to the lower end of this cylindri- 70 cal casing by means of suitable couplings 75 45 is a vertical pipe having an upper portion 46 and a lower portion 47. The lower por- 80 tion 47 of this pipe is connected to the inlet 85 valve 39. The upper portion 46 extends 90 above the point where the outlet valve 40 is connected so that this portion 46 together with the casing 43 include a volume which is 95 preferably several times greater than the

maximum volume of displacement of the ex- pansible chamber of the pump.

When this pump is placed in operation, the entire system, including sections 47 and 46 of the vertical pipe, the chamber 43, and the pump chamber above it, is first entirely filled with liquid. Then upon the upstroke 70 of the pump, liquid is drawn in from the vessel 38 through inlet valve 39 into the vertical pipe. The liquid which is at the 75 junction 48 of the outlet valve 40 with the vertical pipe is drawn up a certain distance above this junction, but because of the fact that the volume of the pump chamber is smaller than the volume of the connections 80 between this junction and the pump chamber, this liquid will not be drawn into the pump chamber itself, but will only rise a relatively short distance in the upper por- 85 tion 46 of the vertical pipe. During the 90 downward stroke of the pump, this liquid which has been raised above the junction 48 is now forced downwardly and out through the outlet valve 40, and into pipe 41 against the pressure due to the head of liquid con- 95 tained in this pipe. The liquid being pumped, therefore, never enters the chamber 95 of the pump, but the direct pumping action upon the liquid being pumped is really caused by a reciprocating liquid piston with- 100 in the upper portion 46 of the vertical pipe. The reciprocation of this liquid piston is caused by the reciprocation of the pump.

100 In order to facilitate the clearing of the pumping chamber and its connecting pas- sages of air when the pump is first placed in operation, and for maintaining these parts free from air, I have provided, in place of the hand-operated valve 23 previously men- 105 tioned, an automatic check valve 49. This valve is arranged to be closed upon the up- 110 ward stroke of the pump and open during its downward stroke. At each downward stroke of the pump, therefore, air will be ex- 115 pelled through the valve 49 until the interior parts of the pump are completely filled with liquid. As soon as liquid begins to issue through the valve 49 a hand-valve 50, provided for the purpose, may be closed. Preferably, however, the hand-valve 50 is 120 always left open, more or less, and the small amount of liquid which is discharged is carried back by means of the flexible connection 51 and the pipe line 52 to the supply vessel 38. In this way the pump chamber is al- 125 ways automatically kept clear of air and because of the relatively large displacement capacity of the pump, the amount of liquid thus escaping is negligible.

125 In this modification, the liquid employed as the liquid piston in the pump chamber, casing 43, and upper portion 46 of the ver- 130 tical pipe, is derived from the liquid being pumped, and is, in practice, when pumping an ore pulp, a relatively clear liquid. The

reason for this is that the agitation of this column of liquid caused by the reciprocation of the pump is insufficient to interfere with the ultimate settling by gravity of the 5 solid particles which the liquid originally contained; nor is the amount of liquid escaping through valve 49 sufficient to cause an appreciable amount of fresh solid material to be added to the reciprocating liquid 10 column.

It is entirely practical, moreover, to introduce a supply of fresh clear liquid from an independent source into the pump chamber and its connecting passages instead of 15 depending upon the settling action just referred to. For example, an independent supply of clear liquid, such as water, may be introduced through the connection 51 and valves 50 and 49, reversing the setting 20 of the latter valve so as to allow liquid to enter during the downward stroke. In this case, the independent liquid supply is under pressure and a relatively small amount of 25 the liquid is kept flowing downwardly through the pump chamber into the cylindrical casing 43 and upper portion 46, where it passes outwardly through the pipe 41 with the liquid being pumped.

By employing the pump of the present invention in this modified form, a relatively thin liquid is maintained in the pump chamber at all times, thus facilitating the operation of the pump.

I claim:

35 1. In a pump, the combination of two relatively reciprocable members forming a pumping chamber therebetween, and a separately formed self-sustaining annular diaphragm joining said members, the marginal 40 edges of said diaphragm being of substantially the same diameter and the intermediate portion thereof being of greater diameter than said edges.

2. In a pump, the combination of two 45 relatively reciprocable members forming a pumping chamber therebetween, and a separately formed self-sustaining annular diaphragm joining said members, the marginal edges of said diaphragm being joined by a 50 relatively inflexible and non-distensible portion of greater diameter than said edges.

3. An expansible chamber for fluid handling devices comprising two relatively reciprocable members forming a fluid-receiving 55 chamber therebetween, and a separately formed self-sustaining annular diaphragm joining said members, the marginal edges of said diaphragm being joined by a non-distensible portion capable of relatively 60 slight transverse flexure at substantially all points thereof.

4. An expansible chamber for fluid handling devices comprising two relatively reciprocable members forming a fluid-receiving 65 chamber therebetween, and an annular

diaphragm joining these members, the diaphragm having a bead along each marginal edge thereof, and means provided on each of the members for engaging one of the beads to secure the diaphragm to the members. 70

5. In a pump, the combination of a casing, a circular head reciprocable with respect thereto and forming a pumping chamber therewith, and a separately formed self-sustaining annular diaphragm having an annular bead along each marginal edge thereof, and means on the casing and the circular head for engaging said beads so as to secure the respective margins of the diaphragm to these members. 75

6. In a pump, the combination of two relatively reciprocable members forming a pumping chamber therebetween, and an annular diaphragm joining these members and having a bead along each of its marginal edges, and a clamping ring removably mounted upon each of the members for engaging one of the beads to removably secure the diaphragm to the members. 80

7. An expansible chamber for fluid handling devices comprising a casing, a circular head reciprocable with respect thereto and forming a fluid-receiving chamber therewith, and a separately formed self-sustaining annular diaphragm having an annular bead along each of its marginal edges and clamping rings mounted upon the casing and the circular head respectively for engaging said beads to removably secure the diaphragm to said members. 90

8. In a pump, the combination of two relatively reciprocable members forming a pumping chamber therebetween, and a substantially tire-shaped annular diaphragm joining said members. 105

9. An expansible chamber for fluid handling devices comprising two relatively reciprocable circular members forming a fluid-receiving chamber therebetween, and a substantially tire-shaped annular diaphragm connecting said members throughout their peripheries. 110

10. In a pump, the combination of a casing, a circular head reciprocable with respect thereto and forming a pumping chamber therewith, and a substantially tire-shaped annular diaphragm having one margin thereof secured to the casing and the other margin secured to the circular head near its periphery. 115

11. An expansible chamber for fluid handling devices comprising two relatively reciprocable members forming a fluid-receiving chamber therebetween, and an annular diaphragm comprising a pneumatic automobile tire casing joining said members. 125

12. In a pump, the combination of two relatively reciprocable circular members forming a pumping chamber therebetween, and an annular diaphragm comprising a

pneumatic automobile tire casing connecting said members throughout their peripheries.

13. In a pump, the combination of a casing, a circular head reciprocable with respect thereto and forming a pumping chamber therewith, and an annular diaphragm comprising a pneumatic tire casing having

one margin thereof secured to the pump casing and the other margin secured to the circular head near its periphery.

10

In testimony whereof I affix my signature.

JOHN M. CALLOW.
